UNITED STATES PATENT OFFICE

107,691

DESIGN FOR AN ATOMIZER

Frederick W. Lohse, Attleboro, Mass., assignor
to T. J. Holmes Company, Inc., Norton, Mass.,
a corporation of Massachusetts

Application April 13, 1937, Serial No. 68,719

Term of patent 7 years

To all whom it may concern:

Be it known that I, Frederick W. Lohse, a citizen of the United States, residing at Attleboro, in the county of Bristol and State of Massachusetts, have invented a new, original, and ornamental Design for an Atomizer, of which the following is a specification, reference being had to the accompanying drawing, forming part thereof.

In the drawing

Fig. 1 is a plan view of an atomizer showing my new design.

Fig. 2 is a side elevation of the atomizer shown in Fig. 1.

Fig. 3 is a front elevation at right angles to the plane of Fig. 2.

The essential feature of my design resides in the parts shown in solid lines.

I claim:

The ornamental design for an atomizer, as shown and described.

FREDERICK W. LOHSE.
